CONTAINER COVER

Franz Neuschaefer, Rye, N. Y.

Application January 10, 1941, Serial No. 373,899

7 Claims. (Cl. 132—78.5)

This invention relates to caps or closures for bottles or other containers. Among other uses the invention is particularly adapted for use on bottles for liquids such as colored finger nail polishes, polish removers, etc.

Closures for bottles of finger nail polish and the like, are often provided with an applicator, for example, in the form of a small brush for extending down into the bottle and having its upper portion fixed within the inside of the closure or cap so that when the closure is removed, the user may apply the applicator with some of the liquid from the bottle thereon to the finger nail or other surface to be treated. According to the present invention, such caps or closures may be formed with an upwardly extending handle portion, integral if desired with the main body portion of the cap, and shaped with three divergent outwardly extending fin portions adapted to be gripped respectively between the user's fingers and thumb when the ends of two fingers and the thumb of the user's hand are brought together in a triangular formation with the fins therebetween. Thus a simple, inexpensive and ideal means is provided for securely gripping the cap portion and for holding it against slipping and turning, so that the applicator may be accurately applied to the desired surface without danger of smearing areas not desired to be colored or treated. The fins comprising this handle portion may be upwardly tapered to a blunt point or otherwise, in a manner to enhance the artistic appearance of the closure, and since the cross-sectional shape of the handle is generally similar to a Y formation, it may be securely gripped by the convenient triangular arrangement of the ends of two fingers and the thumb, thus making it possible to apply the applicator with the same degree of accuracy as could be obtained with a long handled brush, yet without requiring the handle portion to be extended upwardly more than will be convenient for easy packing and shipment of the container assembly.

Also according to a preferred form of the invention, the handle portion of the closure may be constructed and arranged with sufficient weight to at least counterbalance the applicator when the body portion of the closure is resting on its side, and accordingly the applicator will be elevated out of contact with the supporting surface, thus eliminating any danger of smearing the liquid on any article of furniture or the like, on which the closure may be placed. Such a construction will not only hold the applicator elevated from the supporting surface, but at the

same time two of the three fins will contact with such surface, thereby preventing the device from rolling. Hence also any danger that the device will roll, and that the applicator will thus come into contact with any object or fall to the floor, will be eliminated.

If the closure and bottle assembly is used for liquids such as finger nail polish, it is sometimes desirable to form the closure with a protuberance or area having a surface curvature and outline simulating a finger nail. Such area may then be colored so as to be of the same shade as the finger nail polish in the bottle when dried on a finger nail, whereby the buyer may quickly 15 inspect the bottle cap and choose the desired shade of color and readily and accurately compare one of her polished finger nails with the colored area of similar curvature and outline on the bottle cap. With the present invention, such 20 colored areas simulating a finger nail may be conveniently placed at the base of the recesses between the diverging fins of the handle portion. In this position the fins will serve to protect the colored areas during packing, shipment and 25 play of the assembly, and thereby prevent the color from being chipped, worn or soiled. The lower portions of the recesses between the fins may be readily made of such shape that the protuberances simulating the finger nails will conveniently fit therein and so that the side walls 30 of the fins will in effect demarcate the outline of typical pointed finger nails.

Various further and more specific objects, features and advantages of the invention will appear 35 from the detailed description given below, taken in connection with the accompanying drawing which forms a part of this specification and illustrates merely by way of example certain preferred embodiments of the invention. The 40 invention consists in such novel features, arrangements and combinations of parts as are shown and described herein.

In the drawing,

Fig. 1 is an elevational view of a bottle cap 45 constructed in accordance with the invention and in assembled relationship with an applicator and bottle;

Fig. 2 is a top view of a bottle cap such as shown in Fig. 1;

Fig. 3 is a vertical sectional view taken substantially along the line 3—3 of Fig. 1;

Fig. 4 is a side view of the same bottle cap and showing the manner in which the same may be gripped by two fingers and the thumb of the user's hand;

Fig. 5 is a sectional view taken substantially along the line 5-5 of Fig. 1; and additionally showing the arrangement of the ends of the fingers and thumb of the user's hand while gripping the handle portion of the bottle cap;

Fig. 6 is a side view of the bottle cap and applicator of Fig. 1, showing the position which the parts will assume when resting upon a table or other supporting surface;

Fig. 7 is an elevational view of a modified form of the invention; and

Fig. 8 is a sectional view taken substantially along the line 8-8 of Fig. 7 and additionally showing the arrangement of the ends of the fingers and thumb of the user's hand while gripping the handle portion of the cap to remove the same from the container.

As shown in Figs. 1 to 3, the closure may comprise a body portion as at 10. This portion may be threaded as at 11 or otherwise suitably formed interiorly in well-known ways, for detachable engagement with the outlet portion of a bottle as at 12. A suitable cork or rubber washer as at 13 may also be provided within the portion 10 for bringing the same into sealing relationship on the bottle when the cap is threaded on. An applicator as at 14, which may take the form of a small brush, for example, may be normally suspended within the bottle by suitably fixing the upper end of the applicator within a small hole as at 15 formed within the portion 10.

As shown, the handle portion of the closure as at 16 may extend upwardly from the body portion 10 in the form of three fins as 17, 18, 19 protruding divergently outwardly from a generally vertical and central axis of the handle. As shown in Figs. 4 and 5, a channel-like space between two of these fins provides areas for securely engaging the end of the user's thumb for example, while the other two channel-like spaces between the fins similarly provide areas for firmly engaging the ends of two opposed fingers of the user's hand. That is, the handle portion of the closure will have a generally Y-shaped cross section for conveniently and very securely fitting the ends of two fingers and the thumb of the user's hand when brought together in a triangular formation as illustrated in Fig. 5.

As shown in the various figures, the lower portions of the three fins may extend out to approximately the same diameter as the body portion 10 of the closure, while the upper portions of the fins may be gradually tapered for some distance and then more abruptly tapered to a blunt point at the top. The fins do not need to extend upwardly appreciably beyond where they will contact with the ends of the user's fingers when gripping the closure handle portions at points near the main body portion. Yet a sufficiently secure grip is afforded to enable the user to apply the applicator with the same degree of accuracy and steadiness as would otherwise be obtainable only with a long handled artist's type of brush.

At the base of each of the channel-like spaces between the fins, areas as at 20 may be formed with surface curvatures and outlines such as to substantially simulate finger nails. These areas may be colored and of a shade corresponding to that produced by the liquid in the container when used on one's nails. It will be noted that the adjacent walls of the fins will serve to outline these areas so that the same will simulate nails which have been trimmed to a point. In the manufacture of the cap, the walls of the fins

will serve to indicate to the workman when coloring these areas, the proper limits of the area to be colored, and at the same time more distinctively outline the colored finger nail representation. Since as shown, the lower portions of the fins 17, 18 and 19 may readily be made to protrude outwardly somewhat beyond the areas 20, these fins will serve to protect the colored areas 20 against chipping, wearing or soiling of the color during packing, shipment or display of the assembly.

The body and handle portions of the closure may be readily made integral and of any of the well-known molded plastic materials now customarily used for bottle closures or caps. When the assembly is made of such material and of the proportions shown in the drawing, the handle portion will be so arranged and constructed with sufficient weight, to somewhat more than counterbalance the applicator when the body portion is resting on its side as shown in Fig. 6. As a consequence, the applicator will be elevated out of contact with the supporting surface and at the same time two of the fins, for example, fins 18 and 19, will come into contact with the supporting surface. Hence these fins, together with the body portion 10, will provide in effect a three-point contact with the surface and prevent any tendency of the assembly to roll along the surface upon which it is placed. Thus any danger that the applicator and cap will roll into contact with any other object, and danger that the assembly will roll off the support to the floor, is avoided. With the fins of the handle portion upwardly tapered as shown, when the device is placed on its side as Fig. 6, the applicator or brush will be directed slightly upwardly so that any liquid thereon will tend to run back into the cavity within the body portion 10, instead of running to the end of the brush or applicator from which it might drip onto the supporting surface.

In the form of the invention shown in Figs. 7 and 8, the fins 17', 18', 19' may be curved, the curvatures of each fin conforming for example in general to portions of vertical cylinders. At least the vertical elements of each curved fin should preferably conform to straight lines, in order that the article may be readily drawn from a simple form of mold. Also as shown in Fig. 8, the curvatures are preferably in a direction such as to tend to more closely embrace the fingers and thumb on the sides against which pressure is exerted in unthreading the cap from the container. That is, the fins at their outer edges are curved in directions opposite to the direction of rotation of the cap when being unthreaded from the container. Generally more effort is required to remove the cap, than to properly apply it to a container, and there is danger that if considerable pressure is required to do so, the cap will suddenly come loose and slip from the hand. But with the curvature of the fins as shown in Fig. 8, the user is enabled to apply firm pressure against the sides of the ends of two fingers and the thumb in a direction to remove the cap and in such a way that the cap is firmly gripped and danger of slippage prevented. As also best indicated in Fig. 8, the three divergent fins if desired may be unevenly spaced about the central axis so as to provide the most space for the thumb, a space of intermediate size for the second finger, and a smaller space for the first finger. As indicated in Fig. 7, if desired the side walls of the fins may bear, in slight relief, an outline as at

21 simulating the outline of the thumb when in proper position for removal of the cap, thus indicating to the user the manner in which the cap is to be gripped. The nail portion of this outline may if desired, be colored to indicate a shade corresponding to that which will be produced on one's nails by the use of the liquid in the bottle.

While the invention has been described in detail with respect to particular preferred examples, it will be understood by those skilled in the art after understanding the invention, that various further changes and modifications may be made without departing from the spirit and scope of the invention, and it is intended therefore in the appended claims to cover all such changes and modifications.

What is claimed as new and desired to be secured by Letters Patent is:

1. In combination, a bottle closure comprising a body portion, means on the interior of said portion for detachably engaging the outlet portion of a bottle in sealing relationship thereto, an applicator having its upper end secured within the interior of said body portion, whereby the lower portions of the applicator are suspended in the bottle when the closure is applied thereto, and a handle portion extending upwardly from said body portion, said handle portion comprising three fins extending divergently outwardly from a generally vertical and central axis of the handle portion, whereby each side of each fin is adapted to engage the user's thumb or a finger, when the ends of two fingers and of the thumb of the user's hand are brought together in a triangular formation with the fins therebetween said handle portion also being constructed and arranged with sufficient weight to at least counterbalance the applicator when said body portion is resting on its side, to elevate the applicator out of contact with the supporting surface, while two of said fins contact with said surface and prevent the device from rolling.

2. A container cap comprising a body portion formed interiorly with means for detachably engaging the container, and an integral handle portion extending upwardly therefrom and comprising three fins extending divergently outwardly from the vertical axis of the handle portion for fitting between the ends of two fingers and the end of the thumb of the user's hand when said fingers and thumb are brought together in a triangular formation.

3. A container cap comprising a body portion formed interiorly with threaded means for detachably engaging the container, and an integral handle portion extending upwardly therefrom

and comprising three fins extending divergently outwardly from the vertical axis of the handle portion for fitting between the ends of two fingers and the end of the thumb of the user's hand when said fingers and thumb are brought together in a triangular formation, said fins at their outer edges being curved in directions opposite to the direction of rotation of the cap when being unthreaded from the container.

4. A container cap comprising a body portion formed interiorly with means for detachably engaging the container, and an integral handle portion extending upwardly therefrom and comprising three fins extending divergently outwardly from the vertical axis of the handle portion for fitting between the ends of two fingers and the end of the thumb of the user's hand when said fingers and thumb are brought together in a triangular formation, said fins being unevenly spaced angularly about said axis, to provide therebetween a larger channel-like space for the end of the thumb and smaller channel-like spaces for the ends of two fingers.

5. A container cap comprising a body portion formed interiorly with means for detachably engaging the container, and an integral handle portion extending upwardly therefrom and comprising three fins extending divergently outwardly from the vertical axis of the handle portion for fitting between the ends of two fingers and the end of the thumb of the user's hand when said fingers and thumb are brought together in a triangular formation, the outer edges of said fins at the lower portions thereof extending to approximately the same radius as said body portion, and converging upwardly to an apex.

6. A container cap comprising a body portion formed interiorly with means for detachably engaging the container, an integral handle portion extending upwardly therefrom and comprising three fins extending divergently outwardly from the vertical axis of the handle portion for fitting between the ends of two fingers and the end of the thumb of the user's hand when said fingers and thumb are brought together in a triangular formation, and an integral area simulating the contours and outline of a fingernail, located adjacent said body portion and within the channel-like space between two of said fins and protected thereby.

7. A container cap in accordance with claim 2 and having an area simulating, as to outline and color, a finger nail treated with polish, said area being located on the channel-like portion between two of said fins and protected thereby.

FRANZ NEUSCHAEFER.
